UNITED STATES PATENT OFFICE.

ANNIE E. GRAY, OF PHILADELPHIA, PENNSYLVANIA.

DESIGN FOR A COAT.

14,960.

Specification for Reissued Design. Reissued Oct. 19, 1920.

Original No. 55,944, dated August 3, 1920, Serial No. 362,786, filed March 2, 1920, for 3½ years. Application for reissue filed August 16, 1920. Serial No. 404,025. Term of patent 14 years.

To all whom it may concern:

Be it known that I, ANNIE E. GRAY, a citizen of the United States, and a resident of Philadelphia, county of Philadelphia, and State of Pennsylvania, have invented a certain new, original, and ornamental Design for Coats, as shown in the accompanying drawings, in which—

I claim:

The ornamental design for a coat substantially as shown.

In witness whereof I have hereunto set my hand this 12th day of January, A. D., 1920.

ANNIE E. GRAY.
